UNITED STATES PATENT OFFICE.

WILLIAM E. DEPP, OF BROOKVILLE, PENNSYLVANIA, ASSIGNOR OF ONE-HALF TO S. CHAMBERS, OF SAME PLACE.

SPADING-MACHINE.

SPECIFICATION forming part of Letters Patent No. 332,703, dated December 22, 1885.

Application filed August 3, 1885. Serial No. 173,457. (No model.)

To all whom it may concern:

Be it known that I, WILLIAM E. DEPP, a citizen of the United States, residing at Brookville, in the county of Jefferson and State of Pennsylvania, have invented a new and useful Improvement in Spading-Machines, of which the following is a specification, reference being had to the accompanying drawings.

My invention has relation to improvements in spading-machines; and the novelty consists in the construction, combination, arrangement, and adaptation of the various parts for service, substantially as hereinafter fully set forth, and particularly pointed out in the claims.

15 The object of my invention is to provide a spading-machine which shall excavate the earth at predetermined distances for planting potatoes, or to prepare the ground for seed-sowing without the use of a harrow; to regulate the depth of the excavation or cut; to automatically clean the digging or spading implements from the earth or dirt, and thus prevent them from clogging up and becoming inoperative, and to combine simplicity, strength, 25 and durability of construction with efficiency of operation and cheapness of manufacture.

In the drawings hereto annexed, and which form a part of this specification, Figure 1 is a perspective view of a spading-machine constructed in accordance with my invention. Fig. 2 is a longitudinal section on the line xx of Fig 1. Fig. 3 is a detail view of the means for adjusting the supporting-frame bearing-wheels. Fig. 4 is a detailed detached 35 view of one of the eccentric or cam wheels for operating the digging implement or spade. Fig. 5 is a detail view of one of the spading or digging implements. Figs. 6 and 7 are detail views.

40 Like letters of reference indicate like or corresponding parts in all the figures of the drawings, referring to which—

A designates the supporting-frame, comprising parallel side and cross bars, a a' , respectively, suitably connected at their ends in any preferable manner and adapted to form a frame, which is preferably rectangular in form.

45 A' designates the draft-pole, suitably connected to the frame A at its front end.

B B designate the supporting-frame A bearing-wheels, mounted upon short axles b b , which are journaled at one side of the frame in a bracket or standard, D, depending from the frame A near the middle of the side bars thereof, said axles b b being connected to or forming a part of the bent axle C, which comprises two parallel side bars, C C' , arranged under and in alignment with the side bars of the supporting-frame A, and a horizontal cross-bar, C' , connecting the front ends of the bars C together, and serving to support the bent axle C by being journaled in boxes c c , suitably secured to the front cross-bar of the lower face of the frame A, the rear ends of the parallel arms or bars C C' being connected to the short axles b b . The axle C may be made from a single rod, bent to form the parallel bars C C' , the cross-bar C' , and the stub-axles b b , and pivoted at its front cross-bar, C' , in the frame A, and at its rear end in the bracket D, for simultaneously raising and lowering the bearing-wheels B B. The bracket or bar D is provided with a series of teeth at one edge of its upper end, with which meshes a toothed segment, E, pivoted at e to the side bar of the supporting-frame, and having an operating-handle, E' , extending upwardly therefrom above the frame A and within easy reach of the driver, seated in the seat F, supported upon a standard, F', bent as shown, and connected at its lower front end to one of the side bars of the main frame, said seat being arranged at one side of the main frame out of alignment therewith and over the bearing-wheel, in juxtaposition to the operating-handle E' . The handle E' is held in any desired position or adjustment by means of a bolt, G, sliding between perforated lugs g g of the handle, and kept normally in engagement with one of a series of notches, h , formed in a bow or segment, H, by means of a spring, G', arranged between the lugs g g , and coiled over the bolt and bearing at its lower end against a pin passing therethrough. The bolt is retracted from engagement with the notches h of the segment or rack by means of a finger-lever, G², preferably right-angled in form and pivoted upon the upper end of the handle-bar E' , and connected to the bolt G at the upper end.

end thereof by means of a link, G³. The lower arms of the segment H are fitted in mortises formed in one of the side bars of the frame, and are held therein by screws or bolts.

5 I designates the axle for supporting the bearing-wheels J J, arranged on each side of the implement-carrying wheel K, said axle being journaled at its ends in the side bars of the main frame or in suitable boxes or bearings provided therefor, and rigidly held in position therein to enable the bearing and spading wheel to rotate freely thereon. The axle is screw-threaded, as at i, leaving the ends free and plane, on which the hubs j of the bearing-wheels fit, and are held in place by means of nuts j', fitting against the face of said wheels and working on the screw-threaded portion, the bearing and implement wheels being connected together at their outer edges 15 by screw-threaded bolts I', arranged at the periphery of the said wheels and passing through the same, said bolts or rods I' being held in position by means of nuts i' i'', arranged in pairs and adapted to bear on opposite faces 20 of the several wheels, the nuts i'' having a washer, i³, arranged between them and the outer face of the implement-carrying wheel K. The wheels J are preferably made skeleton in form for lightness and strength, are 25 arranged at each end of the axle, and when the machine is in operation they bear upon the surface of the ground and prevent lateral strain upon the axle and implement-carrying wheel K, only one of which is shown in the 30 accompanying drawings for the sake of clearness; but it will be understood that two or more of such implement-wheels K may be employed, as circumstances may require. The wheel K is of the same diameter as the bearing-wheels, and held in position between the bearing-wheels J J by means of the cross-bolts I' and nuts i''. At the periphery of the wheel K it is provided with two lateral flanges, k k, arranged concentric with and a short distance from each other, being separated by an intervening concentric space or groove, k', the flanges being arranged on one of the side faces of the wheel and one below the other. This 35 wheel is without a hub, and lying within the same is a cam or eccentric wheel, L, having a screw-threaded hub, l, fitted on the axle I and held thereon. The eccentric wheel L is made skeleton in form and flat or disk-shaped, except at diametrically opposite points at its 40 periphery, where it is cut away, as at l' l'', and provided with an outwardly-bent and forwardly-projecting cam-tongue, l'', the inner edge of which, where it joins the body of the cam-wheel, being beveled, as at l'', to enable 45 the cross-heads of the spading or digging implements to slide or move freely thereon with a minimum of friction.

M designates the spading or digging implements arranged around the circumference of the carrying-wheel K and exteriorly thereto at one side thereof, said implements comprising a blade, m, rigidly secured upon a shank,

m', having a washer, m², arranged between the lower end of the blade and the exterior face or periphery of the wheel K, to take up the friction and wear thereon. The shanks m' of the spading-implements pass through the flanges k of the wheel K, and are free to rotate therein, said shanks being provided at their lower ends, beneath the inner concentric groove of the carrying-wheel, with two cross-heads, N O, the latter of which is arranged below and at right angles to the former. The cross-head N normally lies transversely across the lower inner face of the lower flange or rim of the 70 wheel, while the other cross-head, O, being arranged at right angles to the cross-head N, normally lies within and parallel with the said flange or rib k, the two cross-heads being connected by an intervening stud, O', and formed 75 integral or cast in one piece with each other. The upper cross-head, N, fits between the under or inner face of the lower flange, k, and the periphery of the cam-wheel L, and when one of the arms of said cross-head comes in 80 contact with the forwardly and upwardly projecting cam-ledge l' of said wheel it turns or revolves the spading-implement shank and lower cross-head, so that the implement-blade will be parallel with the face of the wheel K 85 and the lower cross-head transversely across the same, bringing one of the arms of said lower cross-head, O, in contact with the beveled ledge or portion l'' of said cam-wheel, and upon further rotation of the carrying-wheel the arm in engagement with the beveled ledge l'' will complete the rotation of the 90 implement-blade, so as to cause the same to lie transversely across the face or periphery of the carrying-wheel in their normal position, and rotate or turn the upper cross-head, 95 so as to cause its arms to lie transversely across the inner surface of the flange k, and bring the lower arms of the lower cross-head to lie against and parallel with one of the faces 100 of said cam-wheel until the device or implement comes to the next cam ledge or projection, when the operation above described is 105 repeated.

There may be any number of spading implements arranged around the wheel, and the cam-wheel may have two or more cam tongues or projections.

The blades of the implements may be square and arranged in an inclined position, as shown, 110 or they may be rounded at their cutting-edges, or fork-shaped. The cross-heads may also have beveled faces where they come in contact with the cam-tongue.

It will be observed that the implement-carrying wheel is supported by and rotated with the bearing-wheels J and independently of the axle, and when the cross-heads of the implement come in contact with the cam-wheel tongues they are given a complete turn or rotation, which effectively clears them from dirt or earth.

The bearing-wheels of the main frame can be adjusted up or down, to allow the spades

of the carrying-wheel to go deeper into the earth, by merely withdrawing the bolt G and adjusting the handle-lever forward, the lower serrated segment working in the toothed bracket D, to adjust the wheels and axle to the required degree. The bracket is held in place by means of a guide, D', which bears against the face of said bar D, and is secured to the frame A.

10 The device can be readily converted into a seed-dropper by mounting a hopper on the frame and connecting the slides of said hopper with means—as, for instance, the cross-heads—for being automatically operated by 15 the cam-wheel.

The operation of my invention will be readily understood from the foregoing description, taken in connection with the drawings.

Modifications in details of construction and 20 form and proportion of parts can be made without departing from the principle or sacrificing the advantages of my invention.

Having thus fully described my invention, what I claim as new, and desire to secure by 25 Letters Patent, is—

1. The combination of the main frame, a supporting-axle, bearing-wheels mounted on said axle and rotating independently thereof, an implement-carrying wheel connected to 30 and rotating with the bearing-wheels, a cam-wheel arranged within the implement-carrying wheel and rigidly secured on the axle, and a series of spading implements rotatively mounted in the carrying-wheel, and adapted 35 to be rotated by the rigid cam-wheel when the carrying-wheel is revolved, substantially as described.

2. The combination of the main frame, an axle mounted therein, a cam-wheel rigidly secured to said axle, bearing-wheels mounted 40 on the axle and rotating independently thereof, and an implement-carrying wheel secured upon rods connected with the bearing-wheels and arranged immediately over the cam-wheel, substantially as described.

3. The combination of the main frame, the axle, a cam-wheel rigidly secured on said axle, a rotating wheel arranged over said cam-wheel, and a series of digging implements mounted 50 in the rotating wheel, and having cross-heads at their lower ends adapted to be rotated by contact with the cam-wheel, substantially as described.

4. The combination of the main frame, an 55 axle journaled therein, a cam wheel or disk rigidly secured on the axle, a rotating wheel arranged over said cam-wheel, and a series of digging implements rotatably mounted in said

revolving wheel and arranged around the periphery thereof, substantially as described. 6c

5. The combination of the main frame, an axle supported therein, a cam-wheel rigidly secured on the axle, a revolving wheel arranged over the cam-wheel, and a series of spading implements rotatably mounted in said 65 revolving wheel, and having right-angled cross-heads at their lower ends adapted to be operated upon by the cam-wheel, substantially as described.

6. The combination, with the axle and a revolving wheel, of a cam-wheel and a series of spading implements mounted in the revolving wheel and carrying two cross-heads at their lower ends arranged at right angles to each other, substantially as described. 70

7. The combination, with the axle, a revolving wheel, and a cam-wheel, of a series of spading implements mounted in said revolving wheel and comprising a blade, a shank, and two cross-heads, one below the other, connected together and arranged at right angles to each other, substantially as described. 75

8. The combination of the axle, a cam-wheel rigidly mounted thereon, a revolving wheel arranged over said cam-wheel, and a series of 85 spading implements mounted in said revolving wheel and having two cross-heads, one of which normally lies transversely across the face of the cam-wheel, while the other cross-head lies parallel with its face, substantially 90 as described.

9. The combination of the axle, bearing-wheels mounted thereon, a revolving wheel mounted on cross-bolts secured in the bearing-wheels, a cam-wheel arranged within the revolving wheel, and a series of spading implements rotatably mounted in said revolving wheel and adapted to be operated on by the cam-wheel, substantially as described. 95

10. The combination of the frame, a screw-threaded axle mounted therein, two bearing-wheels having a screw-threaded nut and plain hubs mounted on said axle and free to rotate thereon, a cam-wheel having a screw-threaded hub rigidly secured on the axle, and 100 an implement-bearing wheel arranged over the cam-wheel and mounted upon bars or rods secured in the bearing-wheels and adapted to rotate therewith, substantially as described.

In testimony that I claim the foregoing as 110 my own I have hereto affixed my signature in presence of two witnesses.

WILLIAM E. DEPP.
